UNITED STATES PATENT OFFICE.

MARK SHOELD, OF CHICAGO, ILLINOIS, ASSIGNOR TO ARMOUR FERTILIZER WORKS, OF CHICAGO, ILLINOIS, A CORPORATION OF NEW JERSEY.

PRODUCTION OF NITROGEN.

1,287,472.

Specification of Letters Patent. Patented Dec. 10, 1918.

Application filed March 6, 1918. Serial No. 220,676.

To all whom it may concern:

Be it known that I, MARK SHOELD, a subject of the King of Sweden, residing at Chicago, in the county of Cook and State of Illinois, have invented certain new and useful Improvements in the Production of Nitrogen, of which the following is a specification.

My invention concerns processes or methods for the production of nitrogen and a possible by-product of carbon-dioxid, which under some conditions may constitute the main or principal product and the nitrogen the supplemental or subsidiary gas. Considering the nitrogen as the particularly desirable gas to be produced, the leading and prime objects of the invention are the provision of a method for its supply which shall be continuous in its operation, which shall be economical in its performance, and which shall employ the most ordinary materials or ingredients for its carrying out.

In the preferred method air and fuel are the only ingredients employed and actually consumed and these, of course, are readily available and comparatively inexpensive.

An alkali carbonate solution is also employed in connection with the separation of the carbon-dioxid from the nitrogen but inasmuch as such solution, after its absorption of the carbon-dioxid, is automatically restored to its original condition and is, therefore, used continuously, it is not a source of expense, except to the small extent required to keep the solution up to the desired strength.

In order that those skilled in this art may have a full and complete understanding of the invention and its various advantages, I have illustrated preferred embodiments thereof in the accompanying drawing forming a part of this specification, and throughout the views of which like reference characters refer to the same parts.

In this drawing

Figure 1 illustrates the apparatus for carrying out one method, and

Fig. 2 a modified apparatus used in connection with a slightly different process.

The apparatus used for the performance of the preferred process is illustrated in Fig. 1 and comprises a furnace 10 substantially like a producer furnace except that no steam is used. Such furnace contains a bed 11 of heated coke, the required temperature of

which is maintained without the employment of extraneous heat, by reason of the chemical reaction occurring therein, and such body of fuel may be continuously or intermittently replenished in any approved and convenient manner. Through this furnace, and below its bed of fuel, air is fed or delivered under pressure by a compressor or blower 12 in quantity sufficient to convert the oxygen of the air into carbon-dioxid, whereby the product of such furnace constitutes a gaseous mixture of nitrogen and carbon-dioxid, with possibly a small or practically negligible per cent. of carbon monoxid whose presence in the nitrogen product is not all detrimental when used for some purposes, as, for example, where the nitrogen is availed of in a nitriding furnace for the production of aluminum nitrid.

After passing through a cooler 13, such gaseous mixture is delivered to the lower portion of a scrubber or tower 14 of the usual construction, packed with coke or other suitable material 15. In this appliance, the carbon-dioxid gas is absorbed or separated from the nitrogen of the gaseous mixture, permitting the nitrogen to pass to a cooler 16, where the moisture thereof is condensed, the nitrogen free from moisture, but with possibly a trace of carbon monoxid, issuing from the discharge-pipe 17. This carbon-dioxid absorption is accomplished by delivering into the scrubber at the top a solution of potassium carbonate which, by coming into intimate contact with the carbon-dioxid of the mixture, absorbs the former and is itself converted into potassium bicarbonate solution which flows through a pipe 19 and through one coil 20 of a heat-exchange appliance 21 to a tank 22 maintained at boiling temperature by the application of a small amount of external heat indicated at 23.

Such heating of the potassium bicarbonate solution drives off or expels the carbon-dioxid previously absorbed and steam, which, upon passing through a cooler or condenser 24 issues therefrom through the tube or pipe 25 as practically pure carbon-dioxid without moisture. Thus we have the two desired products, nitrogen, and carbon-dioxid.

When the carbon-dioxid is driven off from the potassium bicarbonate solution, as ex-

plained, the latter is reconverted into a solution of potassium carbonate and such hot solution, by a pump 26, is forced through the other or companion coil 27 of the heat-changer 21 and through a cooler 28 to the pipe 18 and to the scrubber again.

Thus we see that the process is continuous, consuming only air and fuel, and producing the two dissimilar gases, either of which may 10 be the required product and the other the by-product depending upon circumstances.

The furnace 10, although somewhat like a producer furnace differs therefrom in its action and results. In the present process 15 the object is to remove the oxygen from the air so as to leave the desired nitrogen and to remove it in such a way that it can be readily and economically separated from the nitrogen, leaving the latter substantially 20 pure and practically free from diluent gases. In a producer furnace the object is to produce as much carbon monoxide as possible, whereas with the present furnace the purpose is to form carbon-dioxide, the object being 25 to get rid of the objectionable oxygen, or, stated differently, the function of this furnace is to so combine the oxygen with the carbon that it can be readily separated from the nitrogen later on in the process.

30 To those skilled in this art it will be apparent that one or more of the coolers or condensers may be omitted, the piping itself in some cases constituting a sufficient cooler. It is necessary, however, to absorb the carbon-dioxide under cool conditions and to expel it from the solution at a higher heat as specified. It is not required that the heated 35 potassium carbonate solution should be used to raise the temperature of the incoming cool 40 potassium bicarbonate solution, but this, of course, is a feature of economy which reduces the amount of heat necessary to be applied to the tank 22, as well as securing a desired reduction of temperature of the hot- 45 ter solution.

In the process presented above, any suitable alkali carbonate solution may be used, but potassium carbonate solution is preferable to sodium carbonate solution because 50 of the different degrees of solubility of the two carbonates. Caustic soda or sodium hydroxid may be employed, however, in a somewhat different manner. In such case, a caustic soda solution absorbs the carbon-dioxide

in the scrubber, the solution being thereby 55 converted into a solution of sodium carbonate. This, as shown in the apparatus in Fig. 2, flows from the scrubber into a causticizing tank where it is treated with lime, the calcium carbonate settling out and the restored caustic soda solution, whose causticity has been thus revived is, by means of a pump 31, carried back to the top of the scrubber for a repetition of the action. This process is also continuous, but of course, requires the use of lime and is, therefore, under 60 ordinary circumstances, not to be preferred to the other method.

While I have herein set forth only two methods representing desirable ways of taking advantage of this invention, it is to be understood that the latter is not limited and restricted to the precise and exact steps presented nor to the apparatus illustrated and described, because both of these may be modified in many minor respects without departure from the heart and substance of the invention and without the sacrifice of any of its substantial benefits and advantages.

I claim:

1. The process of supplying nitrogen and carbon-dioxide consisting in producing a gaseous mixture of nitrogen and carbon-dioxide, scrubbing such mixture for the removal of the carbon-dioxide therefrom with a chemical solution capable of reacting with said carbon-dioxide thus freeing the nitrogen, then by heat driving off the carbon-dioxide from such modified solution, restoring the latter to its original condition, and transferring 85 the heat of said restored solution to the modified solution, substantially as described.

2. The process of producing nitrogen and carbon-dioxide consisting in supplying air in such quantity to a body of heated carbon as 95 to produce a gaseous mixture composed practically entirely of nitrogen and carbon-dioxide, scrubbing such mixture for the removal of the carbon-dioxide therefrom with an alkali carbonate solution capable of reacting with said carbon dioxide thus freeing the nitrogen, then by heat driving off the carbon-dioxide from such modified solution restoring the latter to its original condition, and transferring the heat of said restored 100 solution to the modified solution, substantially as described.

MARK SHOELD.
